UNITED STATES PATENT OFFICE

2,601,710

SLIDE FASTENER WITH RELEASING
TOP STOPOtto J. Moehler, Newark, N. J., assignor to Com-
mar Products Corporation, Newark, N. J., a cor-
poration of New Jersey

Application June 26, 1948, Serial No. 35,343

14 Claims. (Cl. 24—205.11)

1

This invention relates to slide fasteners, especially top stops for the same, and more particularly to releasing top stops.

In separable slide fasteners provided with a releasing top stop, the slider is stopped by the releasing top stop when drawn with a normal closing force. However, a strong pull causes the slider to move past the releasing top stop, whereupon the stringers are free to be separated by a quick stripping action, without moving the slider back to the bottom stop.

One object of the present invention is to provide a releasing top stop which is inconspicuous; which is adaptable to fasteners of small size; and which does not detract from the finished appearance of commercial slide fasteners.

Other objects are to provide a releasable top stop which does not interfere with the flexibility of the tape, and which has no exposed springs.

Another object of the invention is to provide a releasable top stop which functions to expand the slider within the stem portion thereof in a direction normal or transverse to the plane of the fastener and hence utilizes the most resilient or elastic portion of the slider.

A further object of the invention is to provide a releasing top stop which coacts with the slider but which in operation is independent of many dimensional variations which occur in slider manufacture.

Still another object of the invention is to provide a releasable top stop which may be used with a slide fastener having either a fully separable bottom stop, as in Patent No. 2,381,359 granted to William Milkulas on August 7, 1945, or with a bottom stop which is not fully separable but which is adapted to facilitate reassembly, as disclosed in co-pending application of David Rabinow and the present inventor, filed August 31, 1945, under Serial Number 613,890, now Patent No. 2,573,058 dated Oct. 30, 1951.

To accomplish the foregoing general objects, and other more specific objects which will hereinafter appear, the present invention resides in the slide fastener and releasing top stop members, and their relation one to the other as are hereinafter described in the following specification. The specification is accompanied by drawings, in which:

Fig. 1 is a fragmentary view of a slide fastener embodying the principles of this invention;

Fig. 2 shows the slide fastener in separated condition with the slider pulled past the releasing stop and retained on one stringer;

Fig. 3 is an end view of one of the two releas-

2

ing stop members, and shows how it is clamped on the tape;

Fig. 4 is a plan view with a part of the top slider wall broken away to show the releasing stop members arresting upward movement of the slider;

Fig. 5 is a section taken approximately in the plane of the line 5—5 of Fig. 4;

Figs. 6, 7 and 8 are diagrams explanatory of the operation of the invention;

Figs. 9 and 10 are views similar to Fig. 4 but illustrate progressive stages in the movement of the slider past the releasing end stop when under a strong pull;

Fig. 11 is a longitudinal section taken approximately in the plane of the line 11—11 of Fig. 9;

Fig. 12 is a transverse section taken approximately in the plane of the line 12—12 of Fig. 11;

Fig. 13 is a section similar to Fig. 5, but illustrates a slightly modified form of releasing stop member;

Fig. 14 is a section similar to Fig. 12, but illustrating a modified form of releasing stop member;

Figs. 15, 16, 17, 18 and 19 are diagrams explanatory of the operation of the modified form of the invention; and

Fig. 20 is a perspective view of one of the two releasing stop members.

Referring to the drawings, and in particular to Figs. 1 and 2, the slide fastener comprises stringers 12 and 14 having interlockable fastener elements 16 and a slider 18 movable therealong by means of a suitable handle or so-called "pull" 20. The stringers 12 and 14 respectively are provided with releasing stop members 22 and 24, and stringer 12 is additionally provided with a positive stop member 26 spaced above the releasing stop member 22 by an amount greater than the length of the slider 18. To insure retention of slider 18 on stringer 12, the chain of fastener elements is continued between the releasing stop 22 and the positive stop 26, as is indicated by elements 28. The cords 30 of the stringer 14 are cut off or removed above the releasing stop 24, thereby facilitating disengagement of stringer 14 from the slider.

It will be understood that when the slider is drawn upwardly, its movement is arrested by the top stops 22 and 24. However, if the slider is pulled very forcibly, it moves past the releasing stops 22, 24 to the positive stop 26, as shown in Fig. 2, whereupon the stringer 14 is readily pulled sidewardly from the slider, and the entire length

of the slide fastener is stripped open. It will be seen from inspection of Figs. 1 and 2 that the releasing top stops are inconspicuous, and devoid of flat plates and spring wires of the character heretofore required. Instead, the stop members are small solid metal parts. They are complementary, as is best shown in Fig. 5, their inner edges 32 and 34 being thinned or cut away on opposite sides for overlapping engagement. As here shown, they are sloped to form what may be termed wedge-stop members which assemble in overlapping relation. The operation will be explained in greater detail later, but it may be preliminarily stated at this point that the members 22 and 24 are so dimensioned that when they overlap they exceed the normal height of the slider channel. In the specific form here shown when the height of the wedge-stop assembly equals the height of the slider channel the width of the assembly exceeds the width of the stem portion of the channel, thereby arresting upward movement of the slider, and when the width of the wedge-stop assembly equals the width of the stem portion of the channel the height of the assembly exceeds the normal height of the channel, but does not exceed the height to which the channel may be elastically expanded under abnormal force, so that the slider may be pulled past the wedge-stop assembly by a strong pull.

Referring now to Fig. 4, in moving the slider 18 upwardly or in fastener-closing direction, the stops 22 and 24 enter the divergent branches of the Y-shaped slider channel and move past the neck 36 until they reach approximately the position shown in the drawing. The overall width of the stop members 22, 24 (measured in the plane of the tapes 12 and 14) is such that the stop assembly cannot pass the stem portion of the Y-shaped slider channel. The stops 22 and 24 are, of course, urged toward each other by the convergent ways or flanges 38 of the slider, and the sloping surfaces 32 and 34 overlap somewhat at the bottom. This causes a slight relative displacement of the stops and tapes in a direction transverse of the plane of the tapes, as is shown in Fig. 5, in which the stop 24 has crept up on stop 22 enough to just use up the clearance which the stop members have within the slider. The width of the stop assembly remains greater than the width of the stem portion of the slider channel, and the slider does not move past the stop assembly, under normal force.

If a greater than normal force is applied, the flanges 38 of the slider force the stops 22 and 24 closer toward each other, whereupon the stops spread the slider wings apart.

This action is explained in Figs. 6, 7 and 8, referring to which the slider is assumed to have upper and lower wings 40 and 42, with a channel therebetween having a width W and a height H . This refers to the stem portion of the Y-shaped slider channel. The width W cannot change, but the height H may be elastically expanded, as indicated by the dotted line positions 40' and 42', resulting in a greater channel height H' .

Referring now to Fig. 7, the wedge-stop assembly, made up of stops 44 and 46, has a height H , and has a width W' which is greater than the width W of Fig. 6. However, by changing the relation of the stops to that shown in Fig. 8 the width of the assembly may be reduced to the dimension W , but at the same time the height is increased to a height H' greater than the height H . This height H' is kept within the amount to which the slider may be elastically

expanded, the resilience of the slider causing it to return to normal channel height H after the slider has been forced past the releasing stop assembly.

In Fig. 9, the slide fastener stringers 12 and 14 are completely united up to the stop members 22 and 24, and the slider 18 has been forced upwardly enough to move the stops into parallel relation, with the sloping edges engaging each other throughout their length. This causes a spreading of the slider wings, as suggested in Fig. 6, and as is best shown in Figs. 11 and 12. In Fig. 11 the wings have been spread from the broken line position 40', 42' to the solid line position 40, 42. The material of the slider makes a good spring for this purpose, and I have found that this is true regardless of whether the slider is coined or die cast, riveted or welded, etc.

In Fig. 12 it will be noted that stop 24 and stringer 14 are displaced further upwardly relative to stop 22 and stringer 12, than was the case in Fig. 6. On continued movement of the slider in the same direction, the stop members move through the channel of the slider, as is indicated by the change from Fig. 9 to Fig. 10, until finally the slider moves entirely past the stops. The stringers can now be stripped open from the top, it being remembered that the upper end of stringer 14 above the releasable top stop has no fastener elements and no cord.

The slider, meantime, is stopped by the positive top stop 26, and is retained on stringer 12 by the elements 28 (Figs. 1 and 10). Because of the strong force with which the slider is pulled past the releasable stops, the positive stop 26 may be applied around a fastener element 46 in order to reenforce it.

The releasable stops are preferably secured to the tapes by slotting the outer edges to form jaws which are clamped over the beaded edges of the tapes. Fig. 3 is an end view of the stop member, with the jaws 48 and 50 in spread condition. When the jaws are clamped together around the tape, they assume the broken line position 48', 50'.

In Fig. 3 the stop is the same as that shown in Figs. 5 and 12, that is, it includes a shoulder 52 which strengthens the jaws against opening. However, the stop need not have this cross-section, and instead may have a simple sloping surface such as is shown in Fig. 13, which is generally like Fig. 5, but in which the stop members 54 and 56 do not have shoulders.

Reverting to Figs. 1, 2 and 4, the stop 24 is preferably bevelled at its upper end, as indicated at 58. This is intended to prevent interference with the neck portion of the slider when the slider is moved downwardly after having been pulled upwardly to the normal stop position shown in Fig. 4. It is enough to bevel the stop member 24. However, for the sake of symmetry, and for convenience in production, both members are made identical, and member 22, accordingly, has a bevel 60.

The stop members so far described and illustrated in Figs. 1 to 13 depend for their operation upon the width of the slider between the flanges, for the flanges force the stop members toward each other, this lateral force being translated, through the sloping or wedge faces, into a force exerted upon the inner faces of the slider halves to expand the slider in a direction normal or transverse to the plane of the fastener. However, such a wedging action is not at all essential to the practice of the invention, and a modi-

fication having no lateral wedge action, and which consequently is independent of the exact width of the slider between flanges, is shown in Figs. 14, 15, 17, 19, and 20 of the drawing.

Under ideal conditions the top and bottom sides or "wings" of a slider are in perfect alignment; that is to say, the opposite inner flange surfaces are in exactly the same planes $a-a$ and $b-b$ as shown in Fig. 16. The distance between the coincident planes within the stem portion of the slider channel is designated X . However, in slider manufacture (whether of the two-piece welded or the unitary one-piece variety) there frequently occurs a misalignment of the flanges on opposite slider halves, of the order of one or a few thousandths of an inch. This is illustrated in exaggerated form in Fig. 18, the misalignment being indicated by the dot-dash lines $a'-a'$ and $b'-b'$. In such instances the positions of the inner flanges determine the effective working width of the slider channel. The working width, marked X' in Fig. 18, becomes less than the ideal width X in Fig. 16. Thus, even with careful manufacture there are three variables; the distance between the inner faces of the top and bottom wings, the distance between the flanges of the individual slider halves, and the distance between the innermost flange of one slider half and the innermost flange of the other slider half.

To overcome or eliminate two of these variables, the complementary releasing stop members 70 and 72 in Fig. 14 are designed so that in operation they are independent of the width of the slider channel.

The complementary stop members 70 and 72 are each provided with substantially right angled, confronting surfaces 74, 76 and 78, 80, respectively. The portions 74 and 78 may be termed steps, and the portions 76 and 80, risers. The stop members 70 and 72 may be identical, having the same height Y , which is equal to or less than the normal height of the slider channel. The height of the step Y_a of each stop is slightly greater than half the height of the slider channel, so that when any portion of the steps 74 and 78 are in overlapping relation, the overall height Y' of the assembly is greater than the height of the individual members and the normal height of the channel. The stop assembly then acts to expand the slider to a corresponding channel height Y' as is indicated in dotted lines in Figs. 16 and 18. Preferably, the stops are provided with beveled corner edges 82 and 84 to facilitate the steps 74 and 78 slipping over into overlapping or meshing relation. However, the steps themselves are simply flat and parallel to the flat top and bottom faces of the stops.

Fig. 15 illustrates the position of the stop members prior to their entry into the stem portion of the slider channel. As shown in Figs. 16 to 19, the particular width of the stem portion of the channel is immaterial insofar as achievement of slider expansion is concerned. For a width of say X , the stop members overlap one given amount, as shown in Fig. 17. When the slider channel is of less width, say X' , the stop members overlap a correspondingly greater amount to accommodate themselves to the decrease of channel width. Whatever the actual channel width, the overall height Y' of the assembled, coacting stops, and the consequent position of the slider halves after expansion, is the same for the different widths of channel. The width of each stop member is such that portions of the

flat steps 74 and 78 are in overlapping engagement within the stem portion of the slider channel, even when the channel is of maximum width. The slider flanges 38 function primarily as guides for the stops. They insure some overlap, but the amount of overlap is unimportant. The stops 70 and 72 are each provided with jaws 86, 88 and 90, 92, respectively, to permit clamping upon the beaded edge of their respective tapes 12' and 14'. If desired, one or both of the stop members 70 and 72 may be bevelled at its or their upper end or ends, as indicated at 58 and 60 in Fig. 4, for the same purpose as there ascribed thereto. This is shown at 94 in Fig. 20.

While the slider illustrated is of the welded or two-piece type, it will be understood that the invention contemplates the coaction of the releasing stop members of the present invention with a slider of the unitary or one-piece type as well.

It is believed that the construction and operation, as well as the advantages of my improved slide fastener and its releasing top stop, will be apparent from the foregoing detailed description thereof. The releasing stop members are relatively tiny and inconspicuous, and may be used on many commercial applications of slide fasteners where it would not be feasible to employ some of the cumbersome and unsightly types of releasing stop member heretofore available. The stop members are readily applied by simply clamping the jaws together, one at the end of the fastener elements, and the other by preliminarily removing a single fastener element to make room for the stop. The stop members are inexpensive; have no moving parts; and do not require the use of an exposed spring wire with attendant cost and trouble of assembly. Instead, the slider itself acts as a spring, for although the neck or diamond portion 36 (Fig. 11) is rigid, the opposite end portion, that is the stem portion of the Y-shaped channel, is resiliently separable for a small distance.

It will be apparent that while I have shown and described my invention in several preferred forms, changes may be made in the structures disclosed without departing from the spirit of the invention, as sought to be defined in the following claims.

I claim:

1. A releasing or quick-disassembly top stop for use with a slide fastener including a pair of stringers having interlocking fastener elements, and a slider having a Y-shaped channel, said releasing top stop comprising a pair of complementary stop members which assemble in overlapping relation, said members each having a width in the plane of the tapes and a height in a direction perpendicular to the plane of the tapes no greater than the width and height of the slider channel, whereby either member alone can pass freely through the slider, said members being so shaped, dimensioned, and related that they partially overlap in the stem portion of the slider, and the height of the assembly of the stop members with portions thereof in overlapping relation exceeds the normal height of the stem portion of the channel, but does not exceed the height to which the stem portion of the channel may be elastically expanded, whereby the slider is arrested when pulled with a normal force yet may be pulled past the stop assembly by a strong pull.

2. A releasing or quick-disassembly top stop for use with a slide fastener including a pair

of stringers having interlocking fastener elements and a slider having a Y-shaped channel, the sides of said slider being connected at one end and being slightly resiliently separable at the other end or stem of the Y, said releasing top stop comprising complementary stop members adapted to assemble in overlapping relation when the stringers are brought together by the slider, each stop member being a relatively solid non-resilient block of material having a width less than the width of the slider channel and a height less than the height of the slider channel, the adjacent edges of said stop members being thinned on opposite sides to come into overlapping relation, and said members being so shaped, dimensioned and related that when the members are brought into overlapping relation their combined height exceeds the normal height of the stem portion of the channel, but does not exceed the height to which the stem portion of the channel may be elastically expanded, whereby the slider is arrested when pulled with a normal force, yet may be pulled past the stop assembly by a strong pull.

3. A quick-disassembly slide fastener comprising a pair of stringers having interlocking fastener elements, a slider having a Y-shaped channel, and a releasing top stop assembly, said releasing top stop comprising a pair of complementary stop members which assemble in overlapping relation, said members each having a width in the plane of the tapes and a height in a direction perpendicular to the plane of the tapes no greater than the width and height of the slider channel, whereby either member alone can pass freely through the slider, said complementary stop members being so dimensioned that they partially overlap in the stem portion of the slider, and the height of the assembly with portions of the complementary stop members in overlapping relation, exceeds the normal height of the stem portion of the channel, but does not exceed the height to which the stem portion of the channel may be elastically expanded under abnormal force, whereby the slider is arrested when pulled with a normal force yet may be pulled past the stop assembly by a strong pull, the resilience of the slider causing it to return to normal channel height.

4. A releasing or quick-disassembly top stop for use with a slide fastener including a pair of stringers having interlocking fastener elements, and a slider having a Y-shaped channel, said releasing top stop comprising complementary stop members which assemble in overlapping relation to form a wedge-stop assembly, said members being so shaped, dimensioned, and related that when the height of the wedge-stop assembly equals the height of the slider channel the width of the assembly exceeds the width of the stem portion of the channel, thereby arresting upward movement of the slider when pulled with a normal force, and when the stop members overlap so that the width of the wedge-stop assembly is reduced to the width of the stem portion of the channel the height of the assembly exceeds the normal height of the channel but does not exceed the height to which the channel may be elastically expanded, whereby the slider may be pulled past the wedge-stop assembly by a strong pull.

5. A releasing or quick-disassembly top stop for use with a slide fastener including a pair of stringers and a slider having a Y-shaped channel, said top stop comprising complementary

stop members having a combined width greater than the width of the stem portion of the channel and the inner edges of which are sloped to form wedge-stop members which assemble with the sloping edges in overlapping relation, said members being so dimensioned that when the height of the wedge-stop assembly equals the height of the slider channel the width of the assembly exceeds the width of the stem portion of the channel, thereby arresting upward movement of the slider when pulled with a normal force, and when the width of the wedge-stop assembly is reduced to the width of the stem portion of the channel the height of the assembly exceeds the normal height of the channel but does not exceed the height to which the channel may be elastically expanded under abnormal force, whereby the slider may be pulled past the wedge-stop assembly by a strong pull, the resilience of the slider causing it to return to normal channel height.

6. A releasing or quick-disassembly top stop for use with a slide fastener including a pair of stringers and a slider having a Y-shaped channel, said top stop comprising complementary stop members having a combined width greater than the width of the stem portion of the channel and the inner edges of which are sloped to form wedge-stop members which assemble with the sloping edges in overlapping relation, said members being so dimensioned that when the height of the wedge-stop assembly equals the height of the slider channel the width of the assembly exceeds the width of the stem portion of the channel, thereby arresting upward movement of the slider when pulled with a normal force, and when the width of the wedge-stop assembly is reduced to the width of the stem portion of the channel the height of the assembly exceeds the normal height of the channel but does not exceed the height to which the channel may be elastically expanded under abnormal force, whereby the slider may be pulled past the wedge-stop assembly by a strong pull, the resilience of the slider causing it to return to normal channel height, said wedge-stop members being bevelled at the upper ends of the sloping or wedge-like inner edges to minimize interference with the neck of the slider.

7. A releasing or quick-disassembly top stop for use with a slide fastener including a pair of stringers and a slider having a Y-shaped channel, said top stop comprising complementary stop members having a combined width greater than the width of the stem portion of the channel, said stop members being relatively solid non-resilient blocks of material the outer edges of which are slotted to form jaws clamped over the beaded edges of the tapes of the stringers, and the inner edges of which are sloped to form wedge-stop members which assemble with the sloping edges in overlapping relation, said members being so dimensioned that when the height of the wedge-stop assembly equals the height of the slider channel the width of the assembly exceeds the width of the stem portion of the channel, thereby arresting upward movement of the slider when pulled with a normal force, and when the width of the wedge-stop assembly is reduced to the width of the stem portion of the channel the height of the assembly exceeds the normal height of the channel but does not exceed the height to which the channel may be elastically expanded under abnormal force, whereby the slider may be pulled past the wedge-

stop assembly by a strong pull, the resilience of the slider causing it to return to normal channel height, and said wedge-stop members being bevelled at the upper ends of the sloping inner edges in order to minimize interference with the neck of the slider.

8. A quick-disassembly slide fastener comprising a pair of stringers having interlocking fastener elements, a slider having a Y-shaped channel, a releasing top stop assembly, said releasing top stop comprising complementary stop members the inner edges of which are sloped to form wedge-stop members which assemble with the sloping edges in overlapping relation, said members being so dimensioned that when the height of the wedge-stop assembly equals the height of the slider channel the width of the assembly exceeds the width of the stem portion of the channel, thereby arresting upward movement of the slider when pulled with a normal force, and when the complementary stop members overlap so that the width of the wedge-stop assembly equals the width of the stem portion of the channel the height of the assembly exceeds the normal height of the channel but does not exceed the height to which the channel may be elastically expanded under abnormal force, whereby the slider may be pulled past the wedge-stop assembly by a strong pull, the resilience of the slider causing it to return to normal channel height.

9. A releasing or quick-disassembly top stop for use with a slide fastener including a pair of stringers having interlocking fastener elements, and a slider having a Y-shaped channel, said releasing top stop comprising a pair of complementary stop members which assemble in overlapping relation, said members being so shaped, dimensioned, and related that though the height of each stop member does not exceed the height of the slider channel and the combined width of the assembly of the stop members with portions thereof in overlapping relation in the stem portion of the channel does not exceed the width of said stem portion of the channel, the height of the assembly exceeds the normal height of said stem portion of the channel, but does not exceed the height to which the stem portion of the channel may be elastically expanded, whereby the slider is arrested when pulled with a normal force yet may be pulled past the stop assembly by a strong pull.

10. A releasing or quick-disassembly top stop for use with a slide fastener including a pair of stringers having interlocking fastener elements and a slider having a Y-shaped channel, the sides of said slider being connected at one end and being slightly resiliently separable at the other end or stem of the Y, said releasing top stop comprising complementary stop members adapted to assemble in overlapping relation when the stringers are brought together by the slider, each stop member being a relatively solid non-resilient block of material having a height less than the height of the slider channel, the adjacent edges of said stop members being stepped on opposite sides to come into overlapping relation, and said members being so shaped, dimensioned and related that when the members are brought into overlapping relation their combined width does not exceed the width of the stem portion of the channel yet their combined height exceeds the normal height of said stem portion, but does not exceed the height to which the stem portion of the channel may be elastically expanded,

whereby the slider is arrested when pulled with a normal force, yet may be pulled past the stop assembly by a strong pull.

11. A releasing or quick-disassembly top stop for use with a slide fastener including a pair of stringers having interlocking fastener elements and a slider having a Y-shaped channel, the sides of said slider being connected at one end and being slightly resiliently separable at the other end or stem of the Y, said releasing top stop comprising complementary stop members adapted to assemble in overlapping relation when the stringers are brought together by the slider, each stop member being a relatively solid non-resilient block of material formed at its confronting face with a substantially right angled step portion, said step portion having a slightly greater height than its riser and being provided at its leading edge with a bevel, said stop members each having a total height of step and riser portions less than the height of the slider channel, said members being so dimensioned and related that when the step portions are brought into overlapping relation the combined width of the stop members does not exceed the width of the stem portion of the channel, yet their combined height exceeds the normal height of the stem portion, but does not exceed the height to which the stem portion of the channel may be elastically expanded, whereby the slider is arrested when pulled with a normal force, yet may be pulled past the stop assembly by a strong pull.

12. A releasing or quick-disassembly top stop for use with a slide fastener including a pair of stringers having interlocking fastener elements, and a slider having a Y-shaped channel, said releasing top stop comprising complementary stop members adapted to assemble in overlapping relation when the stringers are brought together by the slider, each stop member having a width less than the width of the slider channel and a height less than the height of the slider channel, the adjacent edges of said stop members being stepped on opposite sides to come into overlapping relation, said steps having a width so great that the members, when overlapped, have a combined width less than the width of the stem portion of the channel, and said steps having a height slightly greater than half the height of the slider channel so that when said members are brought into overlapping relation their combined height exceeds the normal height of the stem portion of the channel, but does not exceed the height to which the stem portion of the channel may be elastically expanded, whereby the slider is arrested when pulled with a normal force, yet may be pulled past the stop assembly by a strong pull.

13. A releasing or quick-disassembly top stop for use with a slide fastener including a pair of stringers having interlocking fastener elements, and a slider having a Y-shaped channel, the sides of said slider being connected at one end and being slightly resiliently separable at the other end or stem of the Y, said releasing top stop comprising complementary stop members adapted to assemble in overlapping relation when the stringers are brought together by the slider, each stop member being a relatively solid non-resilient block of material having a width less than the width of the slider channel and a height less than the height of the slider channel, the adjacent edges of said stop members being stepped on opposite sides to come into overlapping relation, said steps being flat and parallel to the

walls of the stop members, said steps having a width so great that the members, when overlapped, have a combined width less than the width of the stem portion of the channel, and said steps having a height slightly greater than half the height of the slider channel so that when said members are brought into overlapping relation their combined height exceeds the normal height of the stem portion of the channel, but does not exceed the height to which the stem portion of the channel may be elastically expanded, whereby the slider is arrested when pulled with a normal force, yet may be pulled past the stop assembly by a strong pull.

14. A quick-disassembly slide fastener comprising a pair of stringers having interlocking fastener elements, a slider having a Y-shaped channel, a releasing top stop assembly, said releasing top stop comprising a pair of complementary stop members which assemble in overlapping relation, said complementary stop members being so dimensioned that though the height of each does not exceed the height of the slider channel and the combined width of the assembly of the stop members with portions thereof in overlapping relation in the stem portion of the

5
10

channel does not exceed the width of said stem portion of the channel, the height of the assembly exceeds the normal height of said stem portion of the channel, but does not exceed the height to which the stem portion of the channel may be elastically expanded under abnormal force, whereby the slider is arrested when pulled with a normal force yet may be pulled past the stop assembly by a strong pull, the resilience of the slider causing it to return to normal channel height.

OTTO J. MÖEHLER.
